UNITED STATES PATENT OFFICE.

FRANCIS H. MURPHY, OF PORTLAND, OREGON, ASSIGNOR TO PORTLAND RAILWAY
LIGHT AND POWER COMPANY, OF PORTLAND, OREGON, A CORPORATION OF OREGON.

DESIGN FOR A BRACKET AND LAMP FOR STREET ILLUMINATION.

46,913.

Specification for Design.

Patented Feb. 2, 1915.

Application filed August 19, 1914. Serial No. 857,603. Term of patent 7 years.

To all whom it may concern:

Be it known that I, FRANCIS HAYES MURPHY, a citizen of the United States, residing at Portland, in the county of Multnomah, State of Oregon, have invented a new, original, and ornamental Design for a Bracket and Lamp for Street Illumination, of which the following is a specification, reference being had to the accompanying drawings, forming part thereof.

Figure 1 is a side elevational view and Fig. 2 a plan of the bracket and lamp, showing my new design.

I claim:

The ornamental design for a bracket and lamp as shown.

In testimony whereof I have hereunto set my hand in the presence of two subscribing witnesses.

FRANCIS H. MURPHY.

In presence of—

J. C. HENKLE,
W. L. FOLEY.
